(57) **CLAIM**

The ornamental design for a cosmetic container, as shown and described.

DESCRIPTION

FIG. 1 is a perspective view of a first embodiment of our new design for a cosmetic container;

FIG. 2 is a front view thereof;

FIG. 3 is a first side view thereof;

FIG. 4 is a back view thereof;

FIG. 5 is a second side view thereof;

FIG. 6 is a top view thereof;

FIG. 7 is a bottom view thereof;

FIG. 8 is a perspective view of a second embodiment of our new design for a cosmetic container;

FIG. 9 is a front view thereof;

FIG. 10 is a first side view thereof;

FIG. 11 is a back view thereof;

FIG. 12 is a second side view thereof;

FIG. 13 is a top view thereof; and,

FIG. 14 is a bottom view thereof.

The broken lines illustrate structure or features of the cosmetic container that form no part of the claimed design.

1 Claim, 8 Drawing Sheets
